US00D511101S

(12) **United States Design Patent** (10) Patent No.: **US D511,101 S**
 Nottingham et al. (45) Date of Patent: ** Nov. 1, 2005

(54) **ROUND PAINT CONTAINER WITH HANDLE**

(75) Inventors: **John R. Nottingham**, Hunting Valley, OH (US); **John W. Spirk**, Gates Mills, OH (US); **Dale A. Panasewicz**, Strongsville, OH (US); **Nick E. Stanca**, Westlake, OH (US); **Robert Iredell, IV**, Cleveland Hts., OH (US); **Dennis M. Futo**, Strongsville, OH (US)

(73) Assignee: **The Sherwin-Williams Company**, Cleveland, OH (US)

(**) Term: **14 Years**

(21) Appl. No.: **29/194,874**

(22) Filed: **Dec. 2, 2003**

(57) **CLAIM**

The ornamental design for a round paint container with handle, as shown and described.

DESCRIPTION

FIG. 1 is a perspective view of a round pain container with handle embodying our new design;

FIG. 2 is a front elevation thereof;

FIG. 3 is a top plan view thereof;

FIG. 4 is a rear elevational view thereof; and,

FIG. 5 is a right side elevational view thereof.

The broken lines shown in the drawings are for illustrative purposes only and form no part of the claimed design.
